US0D1030590S

(12) **United States Design Patent** (10) **Patent No.:** **US D1,030,590 S**
(45) **Date of Patent:** **** Jun. 11, 2024**

(54) **HEAT SHIELD**

(71) Applicant: **Evolution Powersports LLC**,
Somerset, WI (US)

(72) Inventor: **Todd Zuccone**, Phoenix, AZ (US)

(73) Assignee: **Evolution Powersports LLC**,
Somerset, WI (US)

(**) Term: **15 Years**

(21) Appl. No.: **29/896,391**

(22) Filed: **Jul. 3, 2023**

CLAIM

The ornamental design for a heat shield, as shown and described.

DESCRIPTION

FIG. 1 is a front elevation view of a heat shield with environment incorporating the design; and, FIG. 2 is a perspective view thereof with environment. The portions of the drawings that are de-emphasised as faded out and bound by dashed lines depict environment that forms no part of the claimed design.

1 Claim, 2 Drawing Sheets
